INVENTOR.
Frank F. Wright,
BY
Ralph Burch
ATTORNEY.

UNITED STATES PATENT OFFICE.

FRANK F. WRIGHT, OF AURORA, ILLINOIS.

EAVES TROUGH.

Application filed April 27, 1927. Serial No. 186,920.

My invention relates to improvements in eavestroughs and has for its primary object to provide simple and novel means to prevent the entrance or accumulation of leaves or other refuse matter in the down spout, thus keeping the cistern clean and free from stoppage.

A further object of the invention is to provide means of the above-mentioned character which may be readily attached to the conventional type of eavestrough, without material alterations and which is self-cleaning so as to require no attention after installing.

Another object of the invention is to provide means of the above-mentioned character which is simple and durable in construction, reliable and efficient in operation and inexpensive to manufacture.

Other objects and advantages of the invention will be apparent during the course of the following description.

In the accompanying drawing, forming a part of this specification and in which like numerals are employed to designate like parts throughout the same,

Fig. 1, is a perspective view of my improved eavestrough in use,

Fig. 2, is a perspective view of the elbow detached,

Fig. 3, is an enlarged perspective view showing the elbow attached to the eavestrough, and,

Fig. 4, is a fragmentary longitudinal sectional view of the eavestrough and elbow.

In the drawing, wherein for the purpose of illustration I have shown a preferred embodiment of my invention, the numeral 5 denotes an eavestrough, supported by suitable hangers, not shown, from the eaves or roof of a building. The type of trough shown is substantially semi-circular in cross section having one of its longitudinal edges bent upon itself to provide a tubular bead 5' and is provided at one end, or at spaced intervals, with the usual discharge opening 6, which in this instance is oval shaped and extends approximately the full width of the trough. The opening 6 is surrounded by a depending flange 7, a portion of which is bent upwardly to provide a baffle or lip 8 at one side of the opening adjacent the inner side of the trough, to divert the flow of water to the outer side of the trough, for a purpose to be set forth more fully hereinafter.

The down spout 9 is connected with the discharge opening 6, through the medium of my

improved elbow 10, which as shown more clearly in Fig. 2, is substantially funnel shape. The elbow is preferably formed from a single sheet of metal consisting of an attaching plate 11 curved transversely to conform to the contour of the trough having its end 12 bent at an angle to engage the bead 5' and its opposite end 13, clinched over the inner longitudinal edge of the trough, securely fastening the elbow to the trough. The plate is provided with an opening 14, corresponding in size and shape to the opening 6, which receives the depending flange 7, establishing a water tight connection between the elbow and discharge opening. The body 15 of the elbow extends down from the opening 14 and has an elongated opening 16 through its inner side which merges with the opening 14 at its upper end. A sheet of reticulated metal or filtering member 17 is positioned within the body of the elbow, having its ends bent substantially at right angles to each other, the end 18 covering that portion of the opening 14, adjacent the outer side of the trough and the end 19 covering the lower portion of the opening 16. Thus, it is seen a relatively large opening or space 20 is provided between the angle of the reticulated member and the point of merger between the openings 14 and 16, for the passage of leaves or other refuse matter discharged upon the reticulated member. To assist the percolation of the water through the reticulated member, angle bars 21 are secured at spaced intervals to the bottom thereof.

In use it will be seen that the flow of water in the trough will be diverted, by the lip 8, towards the outer side of the trough, before being discharged into the elbow, so that the water enters the elbow at the extreme upper edge of the screened portion. As the water passes through the screen it is filtered and the leaves or refuse collected by the screen is in turn discharged through the opening or space 20, so that the water entering the elbow is free from foreign matter likely to clog the down spout. The angle bars 21 secured to the bottom of the screen, minimize the tendency of the water to cling to the screen, insuring a free flow of water through the elbow. The device may be readily attached to the conventional type of trough without material alteration and requires no further attention after being installed.

It is to be understood that the form of my invention herewith shown and described is to be taken as a preferred example of the same,

and that certain changes in the shape, size and arrangement of the parts may be made without departing from the spirit of the invention or the scope of the subjoined claims.

5 Having thus described my invention, I claim:

1. The combination with a filtering member having a side opening, of a conduit extending substantially at right angles to said filtering member having a discharge opening communicating with said filtering member, and a baffle member in the conduit adjacent the side nearest the side opening of the filtering member, for the purpose specified.
- 10 2. The combination with a filtering member having a side opening, of a conduit extending substantially at right angles to said filtering member, having a discharge opening communicating with said filtering member, and a baffle struck up from said discharge opening adjacent the side of the conduit nearest the side opening of the filtering member, for the purpose specified.
- 15 3. The combination with a filter consisting of a casing having a side opening and a filtering member covering a portion of the mouth of the casing and the lower portion of the side opening, of a conduit extending at right

angles to said casing having a discharge opening communicating with the mouth of said casing and a baffle in said conduit for diverting the flow of water towards the covered portion of the mouth of said casing.

4. The combination with a conduit having a discharge opening extending substantially the width of said conduit and a downspout, of a funnel shaped member establishing communication between said discharge opening and downspout, said funnel shaped member having an elongated opening through one side thereof, a reticulated member having its ends bent at right angles to each other, disposed in said funnel shaped member, so that one end covers a portion of said discharge opening and the other end covers the lower portion of said elongated opening of the funnel shaped member, whereby a free passage is provided between the upper portion of said elongated side opening and the uncovered portion of said discharge opening and a baffle in said conduit adjacent the uncovered portion of said discharge opening for diverting the flow of water in the conduit towards the covered portion of said discharge opening.

In testimony whereof I affix my signature.
FRANK F. WRIGHT.
